PRIMING MEANS FOR CENTRIFUGAL PUMPS

Edmund F. Doty, Belleville, N. J.

Application May 26, 1934, Serial No. 727,703

3 Claims. (Cl. 103—113)

This invention relates generally to pumps but more particularly to a priming means for centrifugal pumps.

It has for one of its objects to provide a device of this character which is simple, compact and inexpensive in construction, and which is so designed as to effect the priming of the pump in a minimum period of time.

A further object of the invention is to provide an automatic priming device for centrifugal pumps which will in no way interfere with the normal operation of the pump and which has no valves or like parts liable to get out of order.

In the accompanying drawing:—

Figure 1 is a cross section of a centrifugal pump showing my priming means associated therewith. Figure 2 is a longitudinal section taken on line 2—2, Figure 1.

Similar characters of reference indicate corresponding parts throughout the several views.

By way of example, my invention is shown in connection with a centrifugal pump of known construction, the numeral 10 indicating the pump-casing having a centrally arranged impeller chamber 11; 12 indicating suction chambers located at opposite sides of the latter in communication with the suction inlet 13 of the pump-casing; and 14 indicating pressure chambers disposed at opposite sides of the impeller chamber about said suction chambers and communicating substantially tangentially with the main discharge 15 of the pump-casing. Extending centrally through the impeller chamber and suction chambers, and journaled in suitable bearings 16 in the opposite sides of the pump-casing, is a horizontal driving shaft 17 on which the impeller 18 is fixedly mounted. While the impeller may be of any suitable construction, it is shown in the drawing as consisting of spaced disks or shroud plates 19 between which are disposed curved blades 20 suitably spaced to provide fluid passages opening outwardly and enlarging toward the periphery of the impeller in the manner shown in Figure 1. As seen in Figures 1 and 2, the impeller blades extend a suitable distance beyond the peripheral edges of the shroud plates to provide lateral discharge openings or ports 21 which communicate with the adjoining pressure chambers 14. Surrounding the impeller and disposed in proximity to the outer edges of its blades 20 is an impact face or rim 22 which functions to direct the liquid issuing from the impeller in a lateral direction through the ports 21 into the pressure chambers 14.

The means for effecting the priming of the

pump is associated with the discharge side of the pump-casing 10, being automatic or self-controlled, and preferably consists of an air-releasing chamber 23 disposed in a substantially upright position and connected to an elbow-like 5 extension or conduit 24 extending from the pump-casing and containing the main discharge 15 of the pump. A bridge wall 25 divides this conduit to provide the main discharge passage 15 which communicates with the pressure chambers 14, and an auxiliary discharge passage 26 which communicates with the impeller chamber 11 adjacent to the periphery of the impeller 18, as shown in Figure 1. In its lower portion the chamber 23 contains a baffle wall 27 which in 10 effect forms a continuation of the bridge wall 25 in the conduit 24, whereby this chamber communicates with both the main and auxiliary discharge passages 15 and 26, respectively. The upper end of the chamber 23 has connected to it 15 a discharge pipe 28. It is desirable, in the event that a check valve is used in the discharge pipe and there is a head of water above the valve when the pump is stopped or loses its suction prime, to place an automatic air release valve 29 20 in the top of the releasing chamber 23. However, should the pump be used with a free open discharge pipe, then it is unnecessary to use the air release valve.

Before the first priming of the pump, it is 30 necessary to fill the pump casing 10 with liquid to a level at least up to the bottom of the impeller eye in order to furnish the required amount of liquid for producing air entrainment. When the pump is then started up, the priming 35 means comes into operation and there is discharged through the auxiliary passage 26 which is located in the plane of revolution of the impeller-blades 20, columns or pistons of liquid with entrained air, which liquid and air are thence 40 discharged into the releasing chamber 23 where the air is separated from the liquid and passes off through the discharge pipe 28. The liquid utilized in the process of removing the air during the priming operation is recirculated back 45 to the pump casing, this recirculation being caused by a slight difference in pressure between the point where the liquid and air is ejected from the impeller chamber into the auxiliary passage 26 and the point where the liquid is returned 50 to the main discharge passage 15. When the pump is fully primed the liquid is discharged through both passages 15 and 26 and the small pressure difference becomes equalized.

To facilitate the priming operation and reduce 55

to a minimum the time required for priming under certain conditions, I provide a suction trap 30 which may be connected to the suction inlet 13 of the pump casing in the manner shown in Figure 1. This trap functions to maintain a high liquid level in the pump when shut down or for any other reason which may cause it to lose its suction prime.

While I have shown a single auxiliary discharge passage 26, it is to be understood that any number of them may be employed, and where more than one is employed they may be centrally connected to a common passage which in turn is connected to the air-releasing chamber 23.

15 While my invention has been shown in connection with a centrifugal pump of the double-suction horizontal shaft type, it is to be understood that the same is applicable to single stage pumps of the single-suction type or to multistage pumps 20 of either the single or double-suction type, or to vertical shaft pumps including any of the aforesaid types.

I claim as my invention:—

1. A centrifugal pump, comprising a casing 25 having an inlet and a discharge conduit, the latter having a bridge wall therein dividing the same into a main discharge and an auxiliary discharge, an impeller chamber in communication with said inlet and said auxiliary discharge, the latter being 30 in the peripheral plane of said chamber and the main discharge being at one side thereof, an impeller open at its periphery and having lateral discharge openings rotatably mounted in said chamber, a pressure chamber arranged at one 35 side of said impeller chamber and communicating with the same and with said main discharge, reactionary means surrounding the impeller chamber and in proximity to the periphery of the impeller for diverting the fluid through the discharge openings of the latter into said pressure 40 chamber, the impact face of said reactionary means being substantially parallel to the axis of said impeller, and an air-releasing chamber connected to both the main and the auxiliary discharge passages.

2. A centrifugal pump, comprising a casing having an inlet and a discharge, an impeller chamber in communication with said inlet, an im-

peller including blades, open at its periphery and rotatably mounted in said chamber, a pressure chamber arranged at one side of said impeller chamber and communicating with the same and with said discharge, the peripheral edges of the blades being parallel with and extending to the inner wall of the impeller chamber, said impeller having lateral discharge openings intersecting with the periphery thereof and communicating with said pressure chamber and said inner wall 10 of the impeller chamber constituting an impact face for directing the fluid through said discharge openings at substantially right angles to the plane of rotation of the impeller, and an air chamber including a discharge conduit connected to said 15 casing-discharge and having a bridge wall therein dividing the same into main and auxiliary discharges, the auxiliary discharge being connected to the impeller chamber in the plane of the revolving impeller-blades and the main discharge being connected to said pressure chamber. 20

3. A centrifugal pump, comprising a casing having an inlet and a discharge, an impeller chamber in communication with said inlet, an impeller including blades, open at its periphery 25 and rotatably mounted in said chamber, a pressure chamber arranged at one side of said impeller chamber and communicating with the same and with said discharge, the peripheral edges of the blades being parallel with and extending to the inner wall of the impeller chamber, said impeller having lateral discharge openings intersecting with the periphery thereof and communicating with said pressure chamber and said inner wall of the impeller chamber constituting an impact face for directing the fluid through 30 said discharge openings at substantially right angles to the plane of rotation of the impeller, and a discharge conduit connected at one end to said casing discharge and terminating at its other 35 end in a substantially upright portion, said conduit having a bridge wall therein dividing the same into main and auxiliary discharges, the main discharge being connected to said pressure chamber and the auxiliary discharge being connected to the impeller chamber at the periphery of the impeller. 40
